(57) **CLAIM**

The ornamental design for a container gripping device, as shown and described.

DESCRIPTION

FIG. 1 is a top plan view of a container gripping device showing my new design;

FIG. 2 is a front view thereof; and,

FIG. 3 is a front view thereof showing the device engaged with a container.

The bottom plan view is a mirror image of the top plan view. The back view is a mirror image of the front view.

The broken line showing is for illustrative purposes only and forms no part of the claimed design.
